CONNECTER

Frank W. Tronolone, Buffalo, N. Y., assignor to
 Thomas Construction Corporation, Buffalo,
 N. Y., a corporation of New York

Application February 17, 1933, Serial No. 657,265

5 Claims. (Cl. 173—259)

This invention relates to certain new and useful improvements in connectors and particularly to the type for connecting cables or conductors to the terminals or posts of storage batteries.

5 The primary object of the invention is to provide a battery terminal connector embodying a sleeve to be placed in enclosing relation to a battery terminal post combined with a clamping screw for maintaining the sleeve of the connector engaged with the battery post.

10 A further object of the invention is to provide a connector of the foregoing character wherein the connector embodies a cable receiving tube, a post mounting sleeve and a frame portion with which a clamping screw is associated for binding the sleeve on the post with the frame and clamping screw cooperatively constructed to permit detachment of the clamping screw from the frame, but to prevent detachment of said clamping screw when the connector is in service, or with the clamping screw shifted to a position to permit separation of the connector from the battery post.

15 It is a further object of the invention to provide a connector for battery terminals constructed in a manner to provide pockets or crevices for the reception of grease or lubricant to prevent corrosion and to provide a chromium treated lead or other sleeve upon the end of a conductor or cable that is secured to the connector.

20 With the above and other objects in view that will become apparent as the nature of the invention is better understood, the same consists in the novel form, combination and arrangement of parts hereinafter more fully described, shown in the accompanying drawing and claimed.

In the drawing:—

25 Figure 1 is a top plan view of a battery terminal connector constructed in accordance with the present invention showing the clamping screw in its fully retracted inoperative position and disposed to prevent separation of the clamping screw from the frame of the connector;

30 Figure 2 is a side elevational view of the connector;

35 Figure 3 is a bottom plan view of the connector;

40 Figure 4 is an end elevational view of the conductor receiving end of the connector;

45 Figure 5 is an end elevational view of the end of the connector carrying the clamping screw;

50 Figure 6 is a top plan view, similar to Figure 1 showing the clamping screw fully projected

to its forward position and located to permit separation thereof from the frame of the connector;

55 Figure 7 shows top plan views of the connector and clamping screw separated;

60 Figure 8 is a longitudinal sectional view taken on line 8—8 of Figure 1;

65 Figure 9 is a cross-sectional view taken on line 9—9 of Figure 2, with the swivelled clamping plate carried by the screw provided with corner spurs for biting engagement with the battery post;

70 Figure 10 is a cross-sectional view taken on line 10—10 of Figure 2, showing the key hole slot in an end wall of the frame for cooperation with a key or flattened portion on the clamping screw adjacent the head permitting removal of the clamping screw from the frame of the connector;

75 Figure 11 is a cross-sectional view similar to Figure 9 showing the substitution of clamping ribs for spurs; and

80 Figure 12 is a top plan view showing a chromium plated lead or other sleeve upon the end of a conductor inserted in the tube portion of the connector.

85 Referring more in detail to the accompanying drawing, there is illustrated a battery terminal connector 15 including a cylindrical sleeve 16 receivable upon the terminal or post P of the battery B as shown in Figure 2. A cable or conductor receiving tube 17 is carried by one side of the sleeve 16 by means of a connecting neck 18 and said tube is longitudinally split at its outer side as at 19 to permit the positioning of a conductor end therein and relative movements between the split parts of the tube 17 for clamping engagement with the conductor.

90 The side of the sleeve 16 opposite the tube 17 is open and at the open side of the sleeve there is provided a frame including parallel side walls 20, a bottom wall 21, an outer end wall 22 with oppositely disposed inwardly directed ribs 23 carried by the side walls 20 in spaced relation to the outer end wall 22 providing a rectangular pocket 24.

95 The clamping screw 25 of the connector is interlockingly and removably associated with the frame portion, being provided upon one end with a polygonal head 26 with the shank of the screw adjacent the head unthreaded and oppositely flattened as at 27 to provide a reduced key portion. A clamping plate 28 having an arcuate clamping face is swivelled as at 29 upon the threaded end of the screw 25 and said screw

has a rectangular nut 30 threaded thereon and working between the swivelled clamping plate 28 and key portion 27 of the screw shank. To assemble clamping screw 25 with the frame of the connector, the nut 30 is moved over the screw 25 to the end thereof adjacent the key portion 27 of the screw and is placed over the open side of the connector frame, the nut 30 registering with the rectangular pocket 24 and the end wall 22 of the frame provided with an upper edge opening key slot 31 through which the key portion 27 of the clamping screw 25 passes. When the clamping screw is engaged with the frame of the connector, the nut 30 is confined within the pocket 24 while the clamping plate 28 is located between the ribs 23 and closed side of the sleeve 16 as illustrated in Figure 6. Upon rotating the screw 25, the same threads through the nut 30 that is prevented from rotation and displaces the key portion 27 of the clamping screw with respect to the key slot 31 in the end wall 22 of the frame, thereby moving the clamping plate 28 in a direction toward the open side of the sleeve 16 to the position shown in Figure 1 and at which time the same may be placed upon the battery terminal post P as shown in Figure 2. The key slot 31 in the end wall of the frame maintains the clamping screw in assembled relation to the connector 15 when the connector is in service position upon a battery terminal post and also when the connector is out of service, as it is necessary to move the clamping plate toward the open side of the sleeve to permit disconnection of the connector from the battery terminal post. When the connector is in service position, the corner spurs 28a carried by the clamping plate 28 are engaged with the battery terminal post for anchoring the connector thereto, and in lieu of said spurs 28a, the clamping plate 28 as shown in Figure 11 is provided with ribs 28b for biting engagement with the battery terminal post. The pockets or crevices resulting from the assembly of the connector frame and clamping screw may receive grease or lubricant which acts to eliminate corrosion around the battery post.

In the form of invention illustrated in Figure 12, the connector 15a is constructed similarly to the connector 15 shown in Figs. 1 to 11 with the exception that the closed side of the connector opposite the frame portion thereof is open and the sleeve portion 16a carries a transversely extending tube portion 17a that receives a chromium plated lead or other tubing 32 secured to one end of the conductor 33. The tubing 32 extends through the outer open side of the sleeve 16a for direct engagement by the clamping plates 28c, the outer side of the tubing 17a carrying inwardly pressed transversely extending ridges or beads 34 for binding engagement with the chromium plated lead or other tubing 32.

From the above detailed description of the invention, it is believed that the construction and operation thereof will at once be apparent and while there are herein shown and described the preferred embodiments of the invention, it is nevertheless to be understood that minor changes may be made therein without departing from the spirit and scope of the invention as claimed.

I claim:—

75. 1. In a battery terminal connector, a sleeve

for mounting on the post of a battery, a conductor receiving tube at one side of the sleeve, a clamping screw removably carried by the other end of the sleeve and an interlocking connection between the sleeve and clamping screw preventing separation of the screw from the sleeve when the screw is moved to clamping position as in service and retracted position for separation of the sleeve from the post, the interlocking connection including a keyhole slot in a wall of the sleeve and a cooperating key portion on the clamping screw adjacent its outer headed end.

2. In a battery terminal connector, a sleeve for mounting on the post of a battery, a conductor receiving tube at one side of the sleeve, and a clamping screw removably carried by the other end of the sleeve and having an interlocking connection with the sleeve to prevent separation therefrom when the same is moved to clamping position as in service and retracted position for separation of the sleeve from the post, the interlocking connection including a keyhole slot in a wall of the sleeve and a cooperating key portion on the clamping screw, a feed nut for the screw permanently carried thereby and walls within the sleeve providing a separable interfitting connection between the nut and sleeve with the nut respectively frictionally engaged with the walls when the screw is at its limit of movements in opposite directions.

3. In a battery terminal connector, a sleeve for mounting on the terminal post of a battery, a conductor receiving tube at one side of the sleeve, a frame at the other side of the sleeve having an end wall with a key-hole shaped opening therein and an adjacent rectangular pocket, a clamping screw having a key portion at its headed end receivable in the end wall opening, a nut threaded on the screw receivable in the rectangular pocket, and the key portion of the clamping screw being displaced with respect to the key hole opening when the connector is in service position and out of use when the clamping screw is maintained in assembled relation to the connector.

4. In a battery terminal connector, wherein a sleeve is adapted for mounting on the post of a battery, and wherein a bolt, nut and clamp plate assembly is removably attached to the sleeve, means forming a separable interlocking connection between the sleeve and assembly including a key-hole slot in the sleeve and a cooperating key portion adjacent the headed end of the screw whereby the assembly is separable from the sleeve only when the clamp plate is moved in a clamping direction and beyond the normal clamping position of the clamp plate.

5. In a battery terminal connector, wherein a sleeve is adapted for mounting on the post of a battery, and wherein a bolt, nut and clamp plate assembly is removably attached to the sleeve, means to prevent accidental separation of the assembly and sleeve including an interlocking connection therebetween constructed and arranged to prevent separation when the screw is moved to clamping position as in service and retracted position for separation of the sleeve from the post, the interlocking connection being effective for separation of the assembly and sleeve when the clamping screw is operated to move the clamp plate in the direction of and beyond its clamping position, interlocking connection comprising cooperating key and slot portions on the sleeve and bolt.

FRANK W. TRONOLONE.
